UNITED STATES PATENT OFFICE

HANS ROSENTHAL, OF BERLIN, GERMANY, ASSIGNOR TO JULIUS PINTSCH AKTIEN-
GESELLSCHAFT, OF BERLIN, GERMANY

GAS METER

Application filed June 29, 1926, Serial No. 119,339, and in Germany July 1, 1925.

This invention relates to dry gas meters of the type furnished with one single membrane, in which the movement of the membrane is reversed in the end positions by the 5 sudden reversal of inlet and outlet valves.

In the case of such gas meters the necessity for a movement of the membrane which is as even and regular as possible has repeatedly been emphasized, i. e., the resistance 10 which the membrane upon its operation is required to overcome should remain as far as possible the same, in order to prevent fluctuations in the pressure of the gas.

Beyond the provision of a crossed coil 15 spring this object has never in any way been even approximately attained, and even in the case of this known arrangement the second important condition, viz., that the loss of pressure in the meter should be as little as 20 possible, is not entirely fulfilled, since the coil spring is not only tensioned, but due to its tension varies its position, and is continuously required to overcome a by no means in- 25 considerable friction against a surface which is disposed vertically to the direction of movement, this representing a loss in pressure.

The present invention completely eliminates this loss of pressure by friction, i. e., limits the same to the short interval directly 30 prior to the reversal.

In the drawings, Fig. 1 is a vertical section, partly in elevation, of an embodiment of the invention; while Fig. 2 shows a detail section, plan and side view of one of the valve- 35 operating levers.

1 is the membrane, the rod 2 of which moves in either direction in two sheet metal guides 3 and 3¹ which are mounted within the casting of the gas meter. The movement of the 40 membrane is transmitted by means of cords 4, 4¹, running over rolls 5, 5¹, to the cord plates 6, 6¹, which each possess an abutment or extension member in the form of a lever 7 or 7¹. Between the two levers 7 and 7¹ is provided the valve control rod 8, furnished with 45 driving members 9, 9¹, which through the medium of the control levers 10, 10¹ engage with the inlet and outlet valves (not shown). The construction of these levers 10, 10¹ is 50 shown clearly in Fig. 2. It will be seen that

these levers are preferably provided at one end thereof with an eye, the lever arm extending perpendicular to the plane of Fig. 1. At the other end of the lever arm is mounted a rod 10^a which carries the valve member in 55 the usual manner. By displacement of the rod 8, the lever 10 is moved, and the valve rod 10^a is moved in the direction indicated by the arrow P (Fig. 2), thus opening and closing the gas valves. In the normal position the 60 control levers 10, 10¹ are pressed by means of a coil spring 11 against the guides 3 and 3¹. Automatic release of the driving members 9, 9¹ is allowed by provision of the stops 12, 12¹. The operation is as follows:

It is assumed that the membrane moves in the direction indicated by the arrow. This movement causes the cord 4, secured to the plate 6 and the rod 2, to pull on the plate 6, so that the latter rotates and rotates the 70 valve control lever 7 in a clockwise direction. As the rotation of the plate 6 continues the lever arm 7 is increased to the extent necessary for overcoming the counter-pressure which gradually increases by the compression of the spring 11. By the movement of the valve control lever 8, the valve lever 10, by means of the driving member 9 located on the former, is also operated, so that the valves open, viz., for such length of time 75 until the driving member 9 is released by the stop 12¹, when the spring 11 accordingly presses the control lever 10 into the position shown. When the membrane moves towards the left the above operation is repeated in the 80 reversed manner.

What I claim as new and desire to secure by Letters Patent is:

1. In a dry gas meter of the single membrane type, the combination of a membrane, a rotatable member, means connecting said membrane with said rotatable member whereby the rotatable member is rotated upon movement of the membrane in one direction, 90 a lever carried by said rotatable member, a longitudinally movable member engageable and actuatable by said lever, a valve operating member, and spring means connected with said longitudinally movable member 95 100

and detachably connected with said valve operating member.

2. In a dry gas meter of the single membrane type, the combination of a membrane, a rod connected to and movable by said membrane, a rotatable segmental member, means connecting said segmental member with said movable rod to rotate the said segmental member upon movement of the rod, a lever carried by said segmental member, a second rod engageable and movable by said lever, a valve operating member, spring means connected with said second rod and with said valve operating member and serving to actuate said valve operating member on movement of said second rod and means for disconnecting said spring means from said valve operating member when said second rod has moved a predetermined distance.

3. In a dry gas meter of the single membrane type, the combination of a membrane, a rotatable segmental member, means connecting said membrane with said segmental member whereby the segmental member is rotated upon movement of the membrane in one direction, a lever carried by said segmental member, a longitudinally movable member engageable and actuatable by said lever, a valve operating member, and spring means connected with said longitudinally movable member and detachably connected with said valve operating member, and means for automatically disconnecting said spring means from said valve operating member.

4. In a dry gas meter of the single membrane type, the combination of a membrane, a longitudinally movable rod connected thereto, a pair of rotatable members, means connecting said rotatable members to said rod, levers carried by said rotatable members, a second longitudinally movable rod adapted to be engaged at each end by one of said levers and to be moved thereby, valve operating members, and spring means connected with said second mentioned rod and detachably connected with said valve operating members.

5. In a dry gas meter of the single membrane type, the combination of a membrane, a pair of guide members, a rod connected to said membrane and longitudinally movable in said guides, a pair of rotatable members, means connecting said rotatable members to said rod, levers carried by said rotatable members, a second longitudinally movable rod adapted to be engaged at each end by one of said levers and to be moved thereby, valve operating members, and spring means connected with said second mentioned rod and detachably connected with said valve operating members.

6. In a dry gas meter of the single membrane type, the combination of a membrane, a longitudinally movable rod connected thereto, a pair of rotatable members, means

connecting said rotatable members to said rod, levers carried by said rotatable members, a second longitudinally movable rod adapted to be engaged at each end by one of said levers and to be moved thereby, valve operating members, spring means connected with said second mentioned rod and detachably connected with said valve operating members, and means for automatically disconnecting said spring means from said valve operating members. 75 75

7. In a dry gas meter of the single membrane type, the combination of a membrane, a pair of guide members, a rod connected to said membrane and longitudinally movable in said guides, a pair of rotatable members, means connecting said rotatable members to said rod, levers carried by said rotatable members, a second longitudinally movable rod adapted to be engaged at each end by one of said levers and to be moved thereby, valve operating members, spring means connected with said second mentioned rod and detachably connected with said valve operating members, and means for automatically disconnecting said spring means from said valve operating members. 80 85 90

8. In a dry gas meter of the single membrane type, the combination of a membrane, a longitudinally movable rod connected thereto, a pair of rotatable members, means connecting said rotatable members to said rod, levers carried by said rotatable members, a second longitudinally movable rod adapted to be engaged at each end by one of said levers and to be moved thereby, a pair of valve operating members, a pair of blade springs each connected with said second mentioned rod and each detachably connected with one of said valve operating members, and means for automatically disconnecting said springs from said valve operating members. 95 100 105

9. In a dry gas meter of the single membrane type, the combination of a membrane, a longitudinally movable rod connected thereto, a pair of rotatable segmental members, means connecting said rotatable segmental members to said rod, levers carried by said segmental members, a second longitudinally movable rod adapted to be engaged at each end by one of said levers and to be moved thereby, valve operating members, spring means connected with said second mentioned rod and detachably connected with said valve operating members, and means for automatically disconnecting said spring means from said valve operating members. 110 115 120

10. In a dry gas meter of the single membrane type, the combination of a membrane, a pair of guide members, a rod connected to said membrane and longitudinally movable in said guides, a pair of rotatable segmental members, means connecting said rotatable segmental members to said rod, levers car- 130
125

ried by said segmental members, a second longitudinally movable rod adapted to be engaged at each end by one of said levers and to be moved thereby, valve operating members, spring means connected with said second mentioned rod and detachably connected with said valve operating members.

11. In a dry gas meter of the single membrane type, the combination of a membrane, a longitudinally movable rod connected thereto, a pair of rotatable members, a pair of rollers, a pair of cords passing over said rollers and connected at one end to the said rod and at the other end to one of said rotatable members, levers carried by said rotatable members, a second longitudinally movable rod adapted to be engaged at each end by one of said levers and to be moved thereby, valve operating members, spring means connected with said second mentioned rod and detachably connected with said valve operating members.

12. In a dry gas meter of the single membrane type, the combination of a membrane, a longitudinally movable rod connected thereto, a pair of rotatable members, a pair of rollers, a pair of cords passing over said rollers and connected at one end to the said rod and at the other end to one of said rotatable members, levers carried by said rotatable members, a second longitudinally movable rod adapted to be engaged at each end by one of said levers and to be moved thereby, valve operating members, spring means connected with said second mentioned rod and detachably connected with said valve operating members, and means for automatically disconnecting said spring means from said valve operating members.

13. In a dry gas meter of the single membrane type, the combination of a membrane, a longitudinally movable rod connected thereto, a pair of rotatable members, a pair of rollers, a pair of cords passing over said rollers and connected at one end to the said rod and at the other end to one of said rotatable members, levers carried by said rotatable members, a second longitudinally movable rod adapted to be engaged at each end by one of said levers and to be moved thereby, valve operating members, spring means connected with said second mentioned rod and detachably connected with said valve operating members, and stop members for automatically disconnecting said spring members for said valve operating members.

In testimony whereof I have affixed my signature.

HANS ROSENTHAL.
